BED COMFORTER

Harold C. Whitman, Bedford Village, N. Y., assignor, by mesne assignments, to The Esmond Mills, Inc., Esmond, R. I., a corporation of Rhode Island

Application March 20, 1940, Serial No. 325,006

6 Claims. (Cl. 5—334)

My invention relates to improvements in bed comforters.

An object of my invention is to provide a novel type of bed comforter which will eliminate the necessity for stuffing or filling material in the comforter.

It has been shown in Patent No. 2,012,184, issued August 20, 1935, to Boughton Cobb and assigned to applicant's assignee, that pile fibers trapping air cells materially increase the warmth of ordinary blankets. I have observed that something of the same general nature occurs in the filling material of comforters and have realized that if a long nap be raised from the reverse of a blanket which is suitably covered with a light closely woven covering so as to trap air pockets between the long napped fibers thereof that the action is somewhat analogous to the action of the filling material in comforters and that such a lower layer can be substituted for both the light lower layer and filling material of a comforter. I have also discovered that by the employment of a long nap and a closely woven upper layer covering the long nap, that due to the air pockets or air spaces between the fibers of the long nap that these trapping air pockets will provide better insulation than the compact stuffing or filling materials of former types of comforters. This is particularly true if the upper layer be attached to the lower napped layer in a manner to flatten and bend down the upper ends of the upwardly extending pile fibers into a layer of pile fiber ends also supplementally trapping a layer of air cells spaced from said lower layer. Looking at the invention in a different manner, I have discovered that laying a fine cloth, preferably a closely woven upper layer, over the upper surface of such long raised fibers will improve the insulation of the long nap by helping to seal the air spaces in the long nap. I have found by experiment that such long fibers do not stand the wear of rubbing against other blankets on the bed and hence are impractical in use. I have found, however, that the addition of the closely woven upper layer covering the long nap, will protect these long napped fibers from wear so that they may stand up in use.

A further feature of my invention is that this covering cloth tends to keep dust out of the air pockets and cells in the long nap and provides a smooth ornamental upper surface like a comforter.

Further objects of my invention are to provide in a comforter, whether the invention be viewed from the point of view of an improved

comforter or blanket, or improved blanket or comforter insulation, the additional warmth of a lower layer having a napped face, preferably one constructed with a pelage structure of the general type shown in Patent No. 2,012,184 aforesaid.

A further object of my invention is to provide a comforter, which due to the rough lower surface of the blanket lower layer will not slide off the sleeper.

A further feature of my invention is to provide a comforter structure which can be readily washed or otherwise cleaned; more readily than any previous type of a comforter employing a hidden stuffing and one which, with proper care, will at all times be sanitary.

A further object of my invention is to provide a comforter which will comply with the statutes of many States, which now prohibit hidden stuffing and one which also provides more warmth than the former types of comforters.

A further object of my invention is to provide a replaceable covering or upper layer in which the covering cloth may be renewed when worn, it being apparent that it is practically impossible to repair present types of stuffed comforters.

A further object of my invention is to provide, if desired, a comforter of still greater warmth having a face or lower surface constructed of a pelage type of structure of the type shown in said Cobb patent, thereby providing additional warmth to the comforter, it being obvious that the successive layers of pile fibers, whether tucked in, or otherwise, on the face or lower surface of this type of construction tend to form between them a layer or superimposed layers of heat insulating air cells superimposed on said face or lower surface.

A further object of my invention is to provide a comforter which is more durable than former types of comforters.

These and such other objects of my invention as may hereinafter appear will be best understood from a description of the accompanying drawing, which illustrates an embodiment thereof.

In the drawing,

Fig. 1 is a plan view of a comforter having a fine cloth unnapped upper layer and a lower blanket layer constructed in accordance with my invention.

Fig. 2 is a reverse plan view thereof.

Fig. 3 is a side elevation thereof.

Fig. 4 is an enlarged sectional view of a piece of fabric illustrating the type of weave I prefer-

ably employ in the lower layer prior to being napped.

Fig. 5 is an enlarged sectional view of the fabric portion shown in Fig. 4 after pile fibers of varying lengths have been struck up from the lower face thereof and long pile fibers of greater substantial length have been raised from the upper reverse thereof, preferably by a succession of breaker nappers.

Fig. 6 is an enlarged sectional view of the fabric shown in Figs. 4 and 5 after at least the ends of the relative long pile fibers of varying lengths have been tucked into the face by the action of the finisher nappers and showing the upper comforter layer about to be attached thereto.

Fig. 7 is an enlarged sectional view of the fabric shown in Figs. 4 and 5 and said lower fabric layer and upper layer shown in Fig. 6 after the upper layer has been superimposed on the lower layer to flatten and bend down the upper ends of said upwardly extending long pile fibers into a layer of pile fiber ends spaced from said lower layer and with the upper layer suitably fastened to the lower layer at the edges thereof and at intervals throughout the area of said layers to form the comforter.

In the drawing, wherein like characters of reference indicate like parts throughout, 10 generally indicates a comforter constructed in accordance with my invention. Said comforter includes a covering comprising a thin preferably closely woven upper layer 12 and a heavier lower blanket layer 14 suitably secured to said upper layer. I will refer to the lower surface of said lower layer 14 as the face thereof, and the upper surface of said lower layer as the reverse thereof. Means such as stitches 16 are preferably employed to bind the outer edges of said upper and lower layers together and means such as the stitches 20 binding said layers 12 and 14 together at intervals throughout the area of said comforter may also be provided, with the raised upwardly extending long pile threads 18 forming a multiplicity of air insulating pockets, or spaces 17 between said upper and lower layers. Either said stitches 16 binding the edges of said layers together or said stitches 20 preferably bind said upper and lower layers 12 and 14 together so tightly as, in the manner shown, to flatten and bend down the upper ends 19 of said upwardly extending pile fibers 18 into a layer 21 of pile fiber ends 19 spaced from said lower blanket layer 14 entraining a supplemental layer of air cells 23 in said layer 21.

In the usual construction of comforters in place of the long fibers 18, filling material such as feathers, kapok, or other flocculent material has been interposed between the respective upper and lower layers of the comforter. The disadvantage of these filling materials has been, as previously stated, that they are prohibited by statute in certain States, that they are often bound together so tightly as not to have any air insulating spaces, that they accumulate dust and that they can not readily be washed or otherwise cleaned. Employing my invention, however, I dispense entirely with any type of stuffing or filling material and in its place provide a heavier napped reverse for said lower blanket layer 14 having the long pile fibers 18 raised therefrom of substantial length. The lower surface or face of the blanket layer 14 may be suitably napped to provide the pile surface 25. Said pile surface 25 provides a surface having heat insulating pile

fibers respectively entraining one or more layers of heat insulating air cells therein.

While any suitable type of napped blanket face may be provided, I preferably provide the so-called pelage construction explained in detail in said Patent No. 2,012,184 for Fabric and method of making same, issued August 20, 1935, to Boughton Cobb and assigned to applicant's assignee, having the face thereof only treated in accordance with the method described therein to provide an outer layer of tucked in long fibers, such as wool extending substantially over the face or lower surface of said napped fabric and an inner layer or pelage of shorter fibers, such as cotton 15 below said tucked in long fibers. In place of the alternate threads constructed of different fibers shown in the preferred embodiment in said patent, it is apparent that if each individual filling thread be constructed of both long and short 20 fibers of the same species, such as wool fibers of different length and staple or of different species, such as wool and cotton, and if the fabric be subjected to a series of successively longer 25 breaking in napper treatments, that first the short pile threads will be raised therefrom during the initial breaker napper treatment and then longer pile fibers will be successively raised therefrom by successive breaker napper treatments. After the long and short respective pile fibers 30 have been raised from the fabric, simultaneously or successively, the pile fabric may be treated with a finisher napper to tuck in at least the long fibers as shown in said Cobb patent.

It is apparent that I must employ a type of 35 fabric from which the long fibers 18 of substantial length may be raised from the upper surface or reverse thereof and as these fibers are usually raised from filling threads, a suitable type of fabric having a body of filling threads on both 40 the face and reverse thereof is preferably employed.

I have shown in Fig. 4 such a type of suitable 45 fabric having a double twill effect, namely, a twill effect on both the reverse and face thereof. It is apparent that as is well known in the art, a fabric having runs of float threads on the face and reverse provides a better nap, and for this purpose I employ a fabric having float threads of at least the length of a simple twill 50 fabric. While alternate filling threads may be made of long fibers, such as wool and short fibers, such as cotton, each filling thread preferably comprises both long and short fibers, whether of the same or different species and/or 55 staple as previously explained. The fabric shown in Fig. 4 comprises the usual warp threads 24 and the pile forming filling threads 26 floating preferably in twill formation over both the face and reverse of the fabric, pairs of said filling threads 26 being preferably so beaten up as to be superimposed over each other as shown.

I have shown in Fig. 5 the portion of the fabric 60 shown in Fig. 4 after the face thereof has been subjected to a succession of breaking in napping operations of increasing length, the initial breaking in napping operations serving to raise the relatively short pile fibers 30 from the runs of floats of the pile forming filling threads 26 on the face and the longer breaking in napping operations serving to raise the long pile fibers 32 also from the same runs of the same floats of the same filling threads on the face. It is 65 apparent that a succession of breaking in napping operations may be applied to the reverse of the fabric to raise therefrom the long pile fibers 70 75

18 of substantial length, and incidentally the shorter pile fibers 15 therefrom, which breaking in napping operations may be performed on the face and reverse of the fabric successively or simultaneously. It is apparent as I have shown in Fig. 5 that the long and short fibers 30 and 32 and the long pile fibers 18 of substantial length and shorter pile fibers 15 may be raised from the floats of the pile forming filling threads both on the face and on the reverse for a substantial distance through their diameters to provide a relatively large amount of pile formed from the relatively small, preferably loosely woven filling threads 26. I have shown in Fig. 6 the fabric shown in Figs. 4 and 5 after the ends of at least the relatively long pile fibers 32 and preferably also the ends of the short pile fibers 30 have been tucked in to said filling threads 26 or adjacent pile threads as at 34 to form the layer or layers of heat insulating air cells 36 superimposed across the face or lower surface of the lower layer 14. I have shown in Fig. 6 the upper layer 12 in a position above the upstanding long fibers 18 prior to being attached to the lower layer 14 by suitable means such as the stitching 16 binding the edges of said upper and lower layers 12 and 14 together and/or the stitches 20 binding said upper and lower layers 12 and 14 together at intervals through the area of said comforter. As stated, the comforter may be of such a size or the stitches 20 so closely located as to compress the upper layer 12 against said lower layer 14 to flatten and bend down the upper ends 19 of said upwardly extending long pile fibers 18 into a layer 21 of pile fiber ends, entraining the layer 27 of supplemental air cells 23 spaced from said lower layer 14. It is apparent that if desired, however, the upper layer 12 may be joined to the lower layer 14 so as not to provide this layer 21 of pile fiber ends 19 entraining the layer 27 of supplemental cells 23. In both instances, however, the raised upwardly extending long pile threads 18 extending substantially to the closely woven relatively impervious upper layer 12 form a multiplicity of air insulating pockets or spaces 17 between them between said upper and lower layers 12 and 14. It is also obvious that if the layer 21 of pile fiber ends 19 be also formed that a supplemental layer 27 of insulating air cells 23 will also be provided therein. Both the stitching 16 joining the edges of said layers and the stitching 20 joining said layers together at intervals throughout the area thereof may be attached in the same manner as in the manufacture of present-day comforters.

It is also obvious that the upper layer 12 is brought into close contact with the layer 21 of bent over fiber ends 19 to aid in preventing leakage of air through said upper layer, the bent over ends 19 tending to fill in the interstices between the threads of said upper layer 12 to prevent leakage of air through said upper layer. It is apparent that the air cells 36 covering the face of the lower layer supplementally assist in preventing leakage through and providing warmth in the comforter.

It is thus apparent that I have provided a greater number and volume of insulating air pockets and air cells per unit area than is normally provided by the filling material in a standard type of comforter and that if the socalled pelage construction be provided on the face of the lower layer, a comforter having a still greater warmth is provided.

It is also apparent that I have provided a comforter, with a lower rough surface, which will tend to make the comforter stay on and not slip off the bed, which is more durable, sanitary and readily cleaned, with a readily replaceable upper layer and with the other advantages set forth above.

It is understood that my invention is not limited to the specific embodiment shown and that various deviations may be made therefrom without departing from the spirit and scope of the appended claims.

What I claim is:

1. A comforter comprising, a napped fabric lower layer having a heavily napped reverse having long pile fibers raised therefrom of substantial length and shorter pile fibers raised therefrom and a napped face having pile fibers raised therefrom from short pile fibers to pile fibers of substantial length, at least the relatively longer pile fibers having their ends tucked into said threads or adjacent pile threads on said face to provide a fabric having a non-slipable pile face having heat insulating layers of pile fibers forming a multiplicity of insulating air cells superimposed thereon, a light closely woven upper layer, means binding the edges of said upper and lower layers together to form a comforter and means binding said upper and lower layers together at intervals throughout the area of said comforter, whereby the upper ends of said long pile fibers extending upwardly from said reverse are flattened and bent down into a layer of pile fiber ends having insulating air cells therein spaced from said lower layer with the long and shorter pile fibers extending upwardly from said lower layer forming a multiplicity of insulating air pockets between said upper and lower layers.

2. A comforter, comprising, a napped fabric lower layer having a heavily napped reverse having long pile fibers raised therefrom of substantial length and shorter pile fibers raised therefrom and a napped face having pile fibers raised therefrom from short pile fibers to pile fibers of substantial length, at least the relatively longer pile fibers having their ends tucked into said threads or adjacent pile threads on said face to provide a fabric having a non-slipable pile face having heat insulating layers of pile fibers forming a multiplicity of insulating air cells superimposed thereon, a light closely woven upper layer, and means binding said upper and lower layers together at intervals throughout the area of said comforter, whereby the upper ends of said long pile fibers extending upwardly from said reverse are flattened and bent down into a layer of pile fiber ends having insulating air cells therein spaced from said lower layer with the long and shorter pile fibers extending upwardly from said lower layer forming a multiplicity of insulating air pockets between said upper and lower layers.

3. A comforter, comprising, a napped fabric lower layer having a heavily napped reverse having long pile fibers raised therefrom of substantial length and a napped face providing a roughened lower surface to prevent the blanket from sliding off the bed, a light closely woven upper layer, and means binding said upper and lower layers together at intervals throughout the area of said comforter, whereby the upper ends of said long pile fibers extending upwardly from said reverse are flattened and bent down into a layer of pile fiber ends having insulating air

cells therein spaced from said lower layer with the long pile fibers extending upwardly from said lower layer forming a multiplicity of insulating air pockets between said upper and lower layers.

4. A comforter, comprising, a napped fabric lower layer having a heavily napped reverse having long pile fibers raised therefrom of substantial length and shorter pile fibers raised therefrom and a napped face having pile fibers raised therefrom from short pile fibers to pile fibers of substantial length, at least the relatively longer pile fibers having their ends tucked into said threads or adjacent pile threads on said face to provide a fabric having a non-slip-pable pile face having heat insulating layers of pile fibers forming a multiplicity of insulating air cells superimposed thereon, a light closely woven upper layer and means binding the edges of said upper and lower layers together to form a comforter, whereby the upper ends of said long pile fibers extending upwardly from said reverse are flattened and bent down into a layer of pile fiber ends having insulating air cells therein spaced from said lower layer with the long and shorter pile fibers extending upwardly from said lower layer forming a multiplicity of insulating air pockets between said upper and lower layers.

5. A comforter, comprising, a napped fabric lower layer having a heavily napped reverse having long pile fibers raised therefrom of sub-

stantial length and a napped face providing a roughened lower surface to prevent the blanket from sliding off the bed, a light closely woven upper layer and means binding the edges of said upper and lower layers together to form a comforter, whereby the upper ends of said long pile fibers extending upwardly from said reverse are flattened and bent down into a layer of pile fiber ends having insulating air cells therein spaced from said lower layer with the long pile fibers extending upwardly from said lower layer forming a multiplicity of insulating air pockets between said upper and lower layers.

6. A comforter, comprising, a napped fabric lower layer having a heavily napped reverse having long pile fibers raised therefrom of substantial length and a napped face providing a roughened lower surface to prevent the blanket from sliding off the bed, a light closely woven upper layer, means binding the edges of said upper and lower layers together to form a comforter and means binding said upper and lower layers together at intervals throughout the area of said comforter, whereby the upper ends of said long pile fibers extending upwardly from said reverse are flattened and bent down into a layer of pile fiber ends having insulating air cells therein spaced from said lower layer with the long pile fibers extending upwardly from said lower layer forming a multiplicity of insulating air pockets between said upper and lower layers.

HAROLD C. WHITMAN.
